UNITED STATES PATENT OFFICE

137,171

DESIGN FOR A PORTABLE AIRPLANE WORKSHED

John F. Blaski, Chicago, Ill.

Application June 5, 1943, Serial No. 110,368

Term of patent 3½ years

To all whom it may concern:

Be it known that I, John F. Blaski, a citizen of the United States, residing at Chicago, in the county of Cook and State of Illinois, have invented a new, original, and ornamental Design for a Portable Airplane Workshed, of which the following is a specification, reference being had to the accompanying drawing, forming a part thereof.

The figure is a perspective view of a portable airplane workshed embodying my new design.

The dotted line illustration of the airplane is included in the drawing to show better the use of the workshed, the characterizing features of which reside in the portions shown in full lines.

I claim:

The ornamental design for a portable airplane workshed, substantially as shown and described.

JOHN F. BLASKI.
